GARMENT

Albert I. Beldoch, 1410 Broadway,
New York, N.Y. 10018
Filed Mar. 5, 1965, Ser. No. 437,528
2 Claims. (Cl. 2—93)

This invention relates to wearing apparel. More particularly, it relates to improved garments which are highly comfortable to wear and are capable of providing optimum fits for the wearers thereof.

In the construction of a garment, the respective locations of the various necessary seams therein, their angle of disposition, and their shape is determined by many factors, the more important of these factors being comfort, proper fit and prevailing fashion or style.

Known garments are generally constructed to hang from the shoulder of the wearer and generally include shoulder seams which bear the bulk of the weight of the garment. With substantially all of the garment's weight so concentrated as to bear along respective single narrow seams, there consequently results discomfort to the wearer of the garment because of such weight pressing on a narrow and uneven bumpy area of the human body.

These shoulder seams in known garments usually are disposed in a straight line substantially horizontal from the neck to the armhole of the garment. However, the human shoulder does not lie in a straight line but, in fact, curves downwardly from the neck toward the armhole and gently slopes toward the front of the body. Since these anatomical facts have not been considered in the design of known garments and the disposition of the aforesaid shoulder seams therein, the consequence has been the difficulty of providing a proper and total fit therewith.

Since the bulk of the weight of the garment is substantially concentrated along the aforesaid narrow shoulder seam, substantially all of the stress applied to the garment in its wear due to body movements also tends to be concentrated at this seam. With such stress constantly acting on the seam, in addition to the resulting discomfort produced thereby, there is also an increased tendency for the seam to be ripped open or to be torn.

It is, of course, to be noted that some known garment shoulder construction types such as raglan, saddle and the like, substantially eliminate the problems normally encountered in the employment of seamed shoulder constructions, viz., problems such as discomfort, poor fit, tendency to tear and rip, etc. However, as is well known, such raglan and saddle, etc. constructions do not provide the advantages of the more desirable set-in sleeve arrangements.

Accordingly, it is an important object of this invention to provide an improved set-in sleeve type garment construction which provides better qualities of fit, comfort and life of wear as compared to known constructions of like type.

Generally speaking and in accordance with the invention, there is provided a garment having a centrally disposed neckline comprising a front portion and a rear portion, the front portion having an upper edge which comprises a centrally disposed roughly circular concave neckline edge forming section which encloses an area greater than the total area enclosed by the neckline, and a pair of lateral edge sections extending laterally upwardly from the opposite ends of the concave edge section respectively. The front portion also comprises side edges which have at upper parts thereof substantially vertically disposed armhole forming concave edge sections respectively, the lateral end points of the front portion lateral edge sections making respective junctions with

the upper end points of the armhole concave edge sections. The rear portion has an upper edge which comprises a centrally disposed substantially horizontal neckline forming section and a pair of lateral edge sections extending laterally downwardly from the opposite ends of the rear portion neckline forming edge section, the rear portion comprising side edges which comprise, at the upper parts thereof, armhole forming concave edge sections respectively, the lateral end points of the rear lateral edge sections making respective right junctions with the upper end points of the rear armhole concave edge sections. Seams are provided which join opposing respective lateral edge sections to define a closed arc neckline, the seams extending from respectively symmetrically disposed points to the rear of the side to side midline of the area enclosed by the neckline laterally downwardly to respective symmetrically disposed points on the armhole forming concave edge sections of the rear portion.

For a better understanding of the invention together with other and further objects thereof, reference is had to the following description taken in conjunction with the accompanying drawing and its scope will be pointed out in the appended claims.

In the drawing, FIG. 1 shows in front elevation, the front portion of a garment constructed in accordance with the principles of the invention;

FIG. 2 shows in elevation, the rear portion of the garment;

FIG. 3 is an exploded type view showing which edges of the portions shown in FIGS. 1 and 2 are joined to construct the garment; and

FIG. 4 is a three-dimensional view of the assembled garment.

Referring now to the drawing, the front portion 10 thereof as shown in FIG. 1 has an upper edge which comprises a centrally disposed neckline forming edge section 12 and a pair of lateral edge sections 14 and 16 respectively which extend from the end points of section 12 in an upward lateral direction. Front portion 10 comprises side edges, the left edge having an upper concave part 18 and a substantially straight part 20, the right edge having an upper concave part 22 configured to be substantially bilaterally symmetrical with concave part 18 and a substantially straight part 24 substantially co-extensive in length with part 20. Dashed line areas 26 and 28 indicate how sleeves may be set thereinto. It is to be noted that the area 13 enclosed by front portion neckline edge section 12 is more than that of a semi-circle, the significance of which is explained further hereinbelow.

The rear portion 26 comprises an upper edge which has a centrally disposed neckline forming edge section 28 and two lateral substantially symmetrical edge sections 30 and 32 respectively which extend laterally downwardly from the ends of neckline forming edge section 28. The side edges of rear portion 26 comprise upper symmetrical concave parts 34 and 38 respectively and lower straight parts 36 and 40 respectively, edge parts 36 and 40 being substantially equal in length to each other and to edge parts 20 and 24 in front portion 10. As seen in FIGS. 1 and 2, lateral edge portions 14 and 16 make junctions with upper parts 18 and 22 respectively in the front portion 10 and lateral edge portions 30 and 32 make junctions with upper parts 34 and 38 respectively in rear portion 26.

FIG. 3 shows how the various edges of front and rear portions 10 and 26 of the garment are joined by seams to provide the constructed garment of FIG. 4. It is noted that the seams 16-30 and 14-32, because of the selection of front portion neckline forming section 12 to have an arcuate circumference greater than that of a semi-

circle, and the providing of laterally upwardly extending edge sections 14 and 16, run from points 42 and 44 on the neckline defined by edge sections 13 and 28 which are symmetrically disposed and to the rear of the side to side diameter of the area enclosed by the neckline. The respective armholes are defined by the forming of seams 16-30, 14-32, 24-36 and 20-40 (not visible), seams 16-30 and 14-32 extending to points 46 and 48 on the respective armholes. As is seen, points 46 and 48 are to the rear of the side to side midplane of the garment whereby seams 16-30 and 14-32 do not run along the tops of the shoulders but along the back of the garment.

By locating seams 16-30 and 14-32 at the back of the garment instead of along the tops of the shoulders, the fabric constituting the garment lying over the whole area presented by the shoulders absorbs the weight of the garment and distributes it equally. Also the elimination of shoulder located seams greatly enhances the comfort of the garment as experienced by a wearer thereof and there is no conscious pressure felt by the wearer of the garment.

Furthermore, the elimination of the shoulder located seams permits of improved fits not possible with shoulder seamed garments. This results since, with the elimination of the shoulder seams, the garment fabric lies on top of and across the shoulder along a slight bias. This bias provides an added elasticity which permits the fabric to mold itself to the shoulder and conform to its shape as contrasted with the need for the shoulder to conform to the shape of a seam.

It is of course appreciated that the elimination of the shoulder located seams in accordance with the invention results in increased attractiveness of the garment. Thus whereas in a garment with shoulder seams, sharp hard lines are visible along the shoulders giving the garment a square unattractive look, the eliminating of the shoulder seams and locating them at the back as described hereinabove, permits the garment to fall more naturally on the wearer thereof, thereby creating its own shoulder line.

Most important, it is to be noted that the location of the seams on the back of the garment transfers the stress due to body movements from thin relatively weak seam lines to a much larger area of the fabric, i.e., that area covering the shoulders, where the stress is substantially uniformly distributed.

Referring back to FIG. 2 which shows the rear portion of the garment, it is to be noted that the downward angles from which lateral edge sections 30 and 32 extend from the ends of neckline forming edge section 28 is greater than the angle present in the rear portions of known garments. Because of such greater angles, the junction 31 of edge sections 30 and 34 and the junction 33 of edge sections 32 and 38 result in shoulder-armhole intersections which are substantially lower with respect to the shoulder-neckline intersection than in known garments. It is within the contemplation of the invention that the downward angles of edges 30 and 32 be chosen such that the respective shoulder-armhole intersections occur at lower points such as about 2 $\frac{3}{4}$ to 3 $\frac{1}{4}$ inches

lower than the shoulder-neckline intersections. It is also within the contemplation of the invention to provide a contour for rear portion 26 whereby the shoulder neckline intersection is about $\frac{1}{2}$ inch lower than in known garments.

Similarly with regard to front portion 10, as shown in FIG. 1, it is within the contemplation of the invention to have like dispositions of corresponding intersections.

While there has been described what is considered to be a preferred embodiment of the invention, it will be obvious to those skilled in the art that other modifications and changes may be made therein without departing from the invention and it is, accordingly, intended in the appended claims to cover all such modifications as fall within the spirit and scope of the invention.

What is claimed as new and desired to be secured by Letters Patent of the United States is:

1. A garment comprising front and rear portions, said front portion having an upper edge which comprises a centrally disposed roughly circular concave neckline forming section enclosing an area greater than a semi-circle and a pair of lateral edge sections extending laterally upward from opposite ends of said concave section respectively, said front portion having side edges comprising upper part armhole forming concave edge sections respectively, the lateral end points of said lateral edge sections making respective first junctions with the upper end points of said armhole forming concave edge sections, said rear portion having an upper edge 20 which comprises a centrally disposed substantially horizontal neckline forming edge section and a pair of lateral edge sections extending laterally downwardly from the opposite ends respectively of said rear neckline forming section, said rear portion having side edges comprising 25 upper part armhole forming concave edge sections respectively, the lateral end points of said rear portion lateral edge sections making second junctions with the upper end points of said rear armhole concave edge sections, seams joining opposing front and rear lateral edge sections, said seams extending from respectively substantially symmetrically first disposed points on said neckline to the back of the side to side diameter of said neckline to respective second symmetrical points on the armhole forming concave edge sections of said rear portion.
2. A garment as defined in claim 1 in which the angles 30 formed by said rear portion lateral edge sections with said rear portion neckline forming section are so chosen whereby said second junctions are from 2 $\frac{1}{4}$ to 3 $\frac{1}{4}$ inches below the end points of said rear portion neckline forming edge section.
